UNITED STATES PATENT OFFICE

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND

CLASPING DEVICE FOR FLEXIBLE BRACELETS OR THE LIKE

Application filed February 6, 1930. Serial No. 426,407.

This invention relates to flexible bands, chains or linkages for use in the manufacture of articles of jewelry such as bracelets, wrist-watch straps, girdles or the like, and consists particularly in an improved means for clasping the ends of the band or linkage in adjusted relationship.

One object of the invention is to provide a clasping-means adapted for use with bands, chains and linkages constructed from a plurality of articulated link-elements and provided with spaced openings along their length.

Another object of the invention is to provide a clasping-device of the type specified for engagement with the serrated or notched edges of the band, chain or linkage to fasten the ends of the band together.

Another object of the invention is to provide a device of the type specified which is simple in construction and of compact form to adapt it to lie closely against the flat sides of the band, chain or linkage.

Another object of the invention is to provide a device of the type specified which is strong and sturdy in construction and economical to manufacture.

Further objects of the improvement are set forth in the following specification which describes a preferred form of construction of the invention, by way of example, as illustrated by the accompanying drawings. In the drawings:

Fig. 1 is a perspective view representing the ends of two lengths of a metal band or linkage arranged in overlapped relationship and secured together by means of the present improved clasping-device;

Fig. 2 is a plan view of the overlapped ends of the band showing the clasp applied thereto;

Fig. 3 is an edge view of the overlapped ends of the band or linkage showing the present improved clasp in section on line 3-3 of Fig. 2;

Fig. 4 is a similar view showing the clasp released or unfastened;

Fig. 5 is a bottom plan view of the device showing the under part of the clasp broken

away to illustrate the detent-means which retains the parts in closed relationship;

Fig. 6 is a front view of the clasp shown with its parts closed together; and

Fig. 7 is a composite view illustrating the two main elements of the clasp.

The present invention is concerned particularly with flexible bands, chains or linkages similar to that illustrated in my pending application for United States Patent Serial No. 328,761, filed December 27, 1928. In the form of construction therein shown and described the flexible band, chain or linkage comprises a plurality of tubular link-elements arranged in adjacent parallel alignment and connected in articulated relationship by means of U-shaped members inserted into the hollow ends of the adjoining links to straddle the adjoining walls thereof. Linkages of this type are adapted for use as wrist-watch straps or bracelets and are usually provided at their opposite ends with means for attaching them to the bails of the watch. It is desirable that the wrist-watch strap or bracelet be adjustable in length to adapt it to fit wrists of different sizes, and for this purpose the end of one section of the band or linkage is overlapped with the end of the opposite length and made slidably therealong, with the clasping-device adapted to secure the sections in any desired relationship.

As one feature of the present invention the serrated or notched edges of the band or linkage are utilized to provide a series of openings for engagement with means on the clasp to secure the ends of the band in adjusted relationship. Specifically, the present invention contemplates the use in combination with a band or linkage having a serrated edge of a clasp enclosing the opposite sides of the overlying lengths of the band and provided with hinged or otherwise movable means for engaging with the notches or serrations in the edges of the band.

Referring to the drawings, the band, chain or linkage as herein shown is constructed from a series of relatively flat tubular link-elements 2 extending transversely

of the band with their sides in abutting relationship. Inserted into the hollow ends of the flat tubular elements 2 at each side of the band are a series of connecting-elements 3 which may be of any suitable structure, for instance, of bifurcated shape to adapt their legs to straddle the adjoining side walls of two adjacent links. The U-shaped or bifurcated connecting-elements 3 are held in place within the ends of the tubular link-elements 2 by any suitable means, for example, by the interlocking of their legs as shown and described in my pending application for patent hereinbefore referred to. It will be noted from Figs. 2 and 3 of the drawings that the connecting-elements 3 have relatively square ends disposed outwardly beyond the ends of the tubular links 2 and spaced slightly apart along the length of the band or linkage, whereby they form openings or notches 5.

The present improved clasp-device comprises a bottom member 6, shown in detail in Fig. 7, preferably constructed from sheet-metal with a base-strip or plate 7 having opposite upwardly bent flanges 8 at its sides. The flanges 8 are formed at one end with upwardly projecting ears 9 provided with alined holes 10 for receiving a hinge-pin 11, see Figs. 2 and 3. At the opposite ends of the flanges 8 are narrow slots or openings 12 extending parallel with the base-plate 7 and employed for a purpose as later explained.

The upper movable clasp-element or clamp 15 is similar in shape to the bottom member 6, being provided with a top-plate 16 having downwardly bent flanges 17 at its sides. The flanges 17 have ears 18 at their ends, projecting upwardly at the rear of the top-plate 16, their arrangement being opposite to that of the ears 9 on the member 6. The ears 18 are provided with alining holes 19 for the hinge-pin 11 previously mentioned. Bent down from the forward edge of the top-plate 16 are lugs or prongs 20 whose edges abut the sides of the lateral flanges 17. The prongs 20 are adapted to engage in the notches 5 between the edges of the connecting-members 3 for the links 2 of the bracelet above described. The forward edge of the top-plate 16 of the member 15 is curled upwardly at 21 to form a lip under which the finger nail may be inserted to lift the clamp-member to disengage it from the band or linkage. At the forward ends of the flanges 17 the metal is punched in or indented to form projections or protuberances 23 on their inner faces which are adapted to snap into the slotted openings 12 in the flanges 8 of the bottom member 6 when the parts are closed together in clasped relationship. The two elements 6 and 15 are assembled in cooperative relationship in the manner as next explained.

Where the band or linkage is to be used as a wrist-watch bracelet it may comprise two lengths or sections 25 and 26 connected at their ends to the bails of the watch; but in other cases, where used for an ornamental bracelet, the linkage may be made in one length with its ends connected by the clasping-means. The end-link 27 of the length 25 is formed with a circular loop 28, see Figs. 3 and 4, adapted to fit between the ears 9 of the bottom clasp-member 6 and to receive the hinge-pin 11, whereby to anchor this end of the bracelet to the clasp. The upper clasp-member 15 is arranged with its side flanges 17 overlapping the flanges 8 on the bottom member 6, its ears 18 being alined with the ears 9 and the ends of the hinge-pin 11 projecting through the holes 10 and 19 to hinge the upper member to the lower one. In this manner the clasp is attached to the end of the section 25 of the linkage with its upper member or clamp 15 adapted to swivel on the pin 11 to close down on the bottom member 6.

The other section 26 of the linkage is inserted through the clasp above the base-plate 7, and usually the terminal portion of this part of the bracelet is provided with a slide 30 slidable along the section 25. The slide 30 may be constructed of a narrow strip of metal having portions 31 bent down from its ends to enclose the edges of the section 25 of the band and provided with alining holes for receiving a cross-pin 32. The cross-pin 32 extends through a loop in the end-link 33 of the band section 26 with its ends riveted through the holes in the end portions 31 of the slide 30.

In operation, the upper member or clamp 15 of the clasp is swung upwardly or lifted as illustrated in Fig. 4 and the section 26 of the linkage is then free to slide through the clasp to adjust the bracelet to any desired length. After the bracelet has been adjusted about the wrist of the wearer in this manner the clamp 15 is swung down to engage its lugs or prongs 20 with the appropriate notches 5 in the edges of the band section 26. As the clamp 15 is closed down against the bottom member 6 the prongs or projections 20 will slide into the notches 5 and the detent-protuberances 23 on the inner faces of the flanges 17 will snap into the slots or openings 12 in the flanges 8 of the bottom member 6 to lock the parts in closed relationship. With the clamp-member of the clasp thus engaged with the notched edges of the band or linkage the ends will be securely fastened together. When it is required to loosen the bracelet the finger nail is inserted under the lip 21 on the clamp-member 15 to lift the latter to release its projections 20 from the notches in the edges of the band. The two sections of the band may then be drawn out to increase the

length of the bracelet whereby it may be slipped over the hand to remove it from or place it on the wrist.

It will be observed from the foregoing that the present invention provides an extremely simple clasping-device for securing the ends of a strap, band or bracelet in connected relationship. The clasp comprises only two main elements which may be constructed of sheet-metal struck up in dies and assembled by inserting a hinge-pin through the ears 9 and 18 and riveting over its ends. The clamping-member of the clasp makes positive engagement with the edges of the band or bracelet and the detents hold the parts in closed relationship so that the clasp cannot be accidentally released or unfastened. The means for fastening or anchoring the clasp to the end of the bracelet is comprised by the hinge-pin which passes through the terminal link of one section of the band, thus further simplifying the structure of the device and rendering it neater in appearance and less bulky in form.

While the device is herein shown and described as embodied in a preferred form of construction, it is to be understood that modifications may be made in the structure and arrangement of its parts without departing from the spirit or scope of the invention.

Therefore, without limiting myself in this respect, I claim:

1. A clasp for bands or linkages having serrated edges comprising a member having a base-plate adapted to extend across the underside of the linkage and provided with flanges projecting upwardly from its lateral edges, a hinge-pin extending between the side flanges of said member to adapt it to be inserted into the end-link of one section of the linkage, and a clamp-member pivoted on said hinge-pin and provided with lateral flanges adapted to overlap the side flanges of the base-member when the clamp-member is closed down thereagainst, said clamp-member having lugs adjacent its side flanges adapted to engage the serrations in the edges of the linkage to hold the latter in adjusted relationship in the clasp.

2. A clasp for bracelet linkages having notches in the opposite edges thereof comprising a bottom member adapted to extend across the underside of the linkage and provided with flanges at its sides projecting upwardly therefrom, a hinge-pin extending between the flanges for connection with the end-link of the linkage, a clamp-member pivoted on said hinge-pin to adapt it to close down against the top of the bottom member and provided with side flanges overlapping the flanges on the sides of the bottom member, detent-protuberances on the side flanges of one of said clasp-members, openings in the flanges of the opposite member adapted to be engaged by the detent-protuberances to

hold the two members in closed relationship, and lugs on one of said clasp-members adapted to engage through the notches in the edges of the linkage to secure the latter in adjusted relationship in the clasp.

3. In a clasp for bands or linkages having serrated edges, the combination of a bottom member having a base-plate and side flanges bent upwardly therefrom and pierced with holes, a hinge-pin extending through the holes in the flanges, an upper member comprising a top-plate provided with side flanges having holes for receiving the ends of the hinge-pin to pivotally connect said member with the bottom member, detent means on the side flanges of the members adapted to interengage to hold said members in closed relationship, and lugs bent down from the top-plate of the upper member in position to engage the serrations in the edges of the linkage when the top-member is swung down into closed position on the bottom member.

In testimony whereof I hereunto affix my signature.

CHARLES H. KESTENMAN.
